F. F. WITKUS

PRESSER FOOT CONTROLLING DEVICE

Filed June 2, 1923

UNITED STATES PATENT OFFICE.

FRANK F. WITKUS, OF NEWPORT, NEW HAMPSHIRE.

PRESSER-FOOT-CONTROLLING DEVICE.

Application filed June 2, 1923. Serial No. 642,977.

To all whom it may concern:

Be it known that I, FRANK F. WITKUS, a citizen of the United States, and a resident of Newport, in the county of Sullivan, 5 the State of New Hampshire, have invented an Improvement in Presser-Foot-Controlling Devices, of which the following is a specification.

This invention relates to means for so supporting the presser foot, or wheel, of a sewing machine that it may be swung laterally from its normal position adjacent to the needle, after it has been lifted out of contact with the work, to a laterally removed position, in which it will be out of the way of the operator when it becomes necessary to thread or change the needle, or to make other adjustments which would be interfered with by the presser foot or wheel, 20 if in normal position.

In my pending applications, Serial Numbers 581,118 to 581,121, I have shown various means whereby the presser foot will be automatically moved to a lateral position 25 when the presser bar is lifted to a certain point, and the present invention more particularly relates to a specific means for performing this function, which possesses certain advantages over the constructions dis- 30 closed in said applications.

The objects of my present invention are to provide a simple and effective means for positively locking an upwardly swinging presser-wheel-carrying arm in normal position, so that it can not be moved from this position by lateral pressure thereagainst, but which may be unlocked and swung upward from the normal position to a laterally removed position by operating the treadle, 40 or other means, for lifting the presser bar, and, further, to provide means whereby the presser wheel may be locked in a laterally removed position by manually raising the wheel-carrying-arm beyond the point to 45 which it may be raised by the treadle, so that it will be retained in this position, but may be unlocked and returned to normal position by a further depression of the treadle.

I accomplished these objects in the mat-

ter hereinafter described and shown in the 50 accompanying drawings in which:—

Fig. 1 is side elevation of a presser foot mechanism containing an embodiment of my invention.

Fig. 2 is front elevation thereof.

Fig. 3 is a front elevation showing the presser wheel in its raised positions.

Figs. 4, 5, 6, and 7, are detailed views, on an enlarged scale, showing the locking mechanism in different positions.

As my invention is applicable to almost any well known type of sewing machine, only those parts are shown which directly cooperate with the parts to which my invention relates.

As shown in the drawings, the needle bar casing 1 is shown as provided with the usual vertically movable presser bar 2, which is downwardly spring pressed and is adapted to be lifted either by a hand lever, or by a foot, or leg operated lever beneath the machine table, said lever usually being connected to the presser bar through a chain, or similar means, by means of a collar 3, directly attached to the bar. A head or 70 block 4 is clamped on the lower end of the presser bar, and the means for supporting the presser wheel 5 is connected thereto, said means comprising a rod 6, to one end of which the shaft is attached, and on which the wheel is rotatably mounted, the opposite portion of said rod being adjustably secured in the socket of an arm 7, which is mounted for swinging movement about a horizontal axis between bearing screws 8, 75 threaded in lugs on the head 4. A lever 10, having right angularly disposed arms 10^a, 10^b, is mounted on a pivot 11 to swing about a horizontal axis within the head 4, and a spring 12 is interposed between the head 4 and the arm 10^a, in position to swing the arm 10^b upwardly. The arm 10^b of said lever is provided with a face 14, at its extreme end, and with a shoulder 15 on its upper side, closely adjacent to said end.

The arm 7 is provided with a pair of fingers 16 and 17, which project therefrom at the opposite side of its pivot from the portion

thereto which supports the presser wheel, said finger 16 having a face at its end so arranged that, when the presser wheel is in its normal position, it will be in abutment 5 with the face 14 on the end of the arm 10^b. The arrangement of said faces with relation to each other and to the pivot 11 is such that, when said faces are in abutment, the thrust of the face of the arm 16 on the 10 face 14 will be in a line which will intersect the center of pivot 11, so that the arm 7 will be positively locked in normal position, as shown in Figs. 2 and 4. A rod 18 is mounted in the head 4 to slide vertically 15 therein, the lower end of said rod resting on the horizontally disposed arm 10^b of the lever 10.

When the parts are in the position of Fig. 4 and the means for lifting the presser bar 20 are operated, the presser wheel will be lifted from the work sufficiently to permit the position of the work to be shifted. On further lifting movement the rod 18 will be engaged with the underside of the casing and forced 25 downward, thereby causing the arm 10^b to be swung downward against the upper side of the finger 17, and out of engagement with the end of the finger 16. Continued downward pressure on the finger 17 causes the 30 same to be swung downward and the arm 7 to be swung upwardly, and this movement may be continued until the arm is raised to the full line position of Fig. 3, the relative positions of the finger 17 and lever arm 10^b, at the end of said upward movement, being 35 shown in Fig. 7. If pressure on the lifting means is then removed, the spring 12 will return the lever 10 to normal position, thereby causing or permitting the pressure wheel 40 also to be returned to, and locked in normal position. If, however, it is desired to have the wheel locked in a position remote from the needle, so that pressure on the presser-bar lifting means will not have to be continued, to maintain it in such a position, after swinging the arm 7 upwards, to the 45 full line position of Fig. 3, the operator will merely swing the arm 7 upwardly by hand to the dotted line position of Fig. 3. In moving the parts to this position, the end 50 face of finger 16 will pass the shoulder 15, so that the upper side of the said finger will engage said shoulder, as shown in Fig. 6, and thus lock the arm 7 positively against return movement. When it is desired to lower 55 the presser wheel again, the presser bar is again lifted to its fullest extent, causing the arm 10^b to be depressed until the shoulder 15 is disengaged from the end of the finger 60 16. The arm 7 will then be permitted to swing downward slightly by gravity, so that the finger 16 will be carried past the shoulder 15, to the position of Fig. 7, then, when pressure on the lifting means is removed,

the wheel will be free to swing downwardly 65 and to return to its normal position.

I claim

1. In a machine of the character described, a vertically movable support, a presser-foot-carrying arm pivotally mounted on said support and arranged to be swung upwardly to carry the foot from its normal to a laterally removed position, a locking lever arranged to lock said arm against swinging movement when in normal position, and means arranged to move said lever, when said support is lifted, to unlock said arm and swing the same upwardly. 70

2. In a machine of the character described, a vertically movable support, a presser-foot-carrying arm pivotally mounted on said support and arranged to be swung upwardly to carry the foot from its normal to a laterally removed position, a projection on said arm having an abutting face, a locking lever having a face arranged to engage said abutting face to lock said arm in normal position, means arranged to move said lever, upon lifting movement of said support, to disengage said faces and unlock said arm, and to engage said arm and swing it upwardly 75 from said position. 80

3. In a machine of the character described, a vertically movable support, a presser-foot-carrying arm pivotally mounted on said support and arranged to be swung upwardly to carry the foot from its normal to a laterally removed position, a locking lever arranged to engage said arm at one point to lock the same against movement from normal position, and to be moved to unlock the same and engage it at another point to swing it upwardly from said position when said support is lifted, and means on said lever arranged to be engaged by said arm when manually lifted above the point to which it may be raised by said lever to lock said arm in a raised position. 90

4. In a machine of the character described, a vertically movable support, a presser-foot-carrying arm pivotally mounted on said support and arranged to be swung upwardly to carry the foot from its normal to a laterally removed position, a locking lever arranged to engage said arm to lock the same against movement from normal position, and to be moved to unlock the same and swing it upwardly from said position when said support is lifted, an abutment on said lever arranged to be engaged by said arm when manually lifted to an extreme position to lock the same in such position, and to be disengaged on depression of the lever to unlock the arm and permit its return to normal position. 100

5. In a machine of the character described, a vertically movable support having a presser foot mounted therein, and arranged 110

for lateral upward movement from its normal position, means for positively locking said foot automatically when it is moved into said position, means for unlocking the 5 foot and moving it laterally upward to a laterally removed position when said support is raised to a predetermined extent,

means whereby said foot may be manually raised above said laterally removed position, and means for automatically locking the 10 foot in such position when raised thereto.

In testimony whereof, I have signed my name to this specification.

FRANK F. WITKUS.
